MAGNETIC RECORDER

William P. Patrick, Vaughn, Wash.

Application August 24, 1936, Serial No. 97,656

8 Claims. (Cl. 179—100.2)

This invention relates to magnetic recorders of a type adapted to record electrical disturbances on wire and afterwards to reproduce the disturbances which have thus been recorded on the wire.

A primary object of this invention is to provide a simple, efficient and satisfactory apparatus for handling recording wire in such a manner that it may be passed in either direction through one or more heads capable of recording electrical disturbances on said wire or of reproducing from said wire previously recorded electrical disturbances.

Another object of this invention is to provide apparatus for handling recording wire in such a manner that the speed of the wire through the heads is always constant and the tension of the wire is always substantially constant.

Another object is to provide means for passing wire through electromagnetic heads and switching the control from one head to another in such a manner that when the recording of a series of electrical disturbances is complete it will always be possible to start without delay and reproduce the recorded series of disturbances.

Another object is to provide a device of this nature in which a reproducing mechanism can be made to follow very closely after a recording mechanism on a wire to reproduce electrical disturbances within a short period of time after they are recorded.

Another object is to provide a magnetic record in a wire, which record is substantially permanent in its nature and to further provide such a record in a fine, flexible, non-bulky wire which may readily be transported from place to place for reproduction.

Another object is to provide an electromagnetic recording and reproducing device embodying a plurality of heads and a section of wire devoted to the use of each head in such a manner that each section of wire is capable of being passed in either direction through its corresponding head either for the purpose of recording on said wire or reproducing from said wire.

In magnetic recorders employing wire, difficulty has heretofore been encountered in handling the wire and feeding the same through the recorder heads. Devices of this type employing spools or drums in such a manner that the wire is wound from one spool or drum to another usually allow the wire to pile up on the spools or drums. With these devices it is difficult to keep the wire moving at a constant speed due to the fact that when wire is winding onto a drum

it progressively increases the effective diameter onto which it is winding and when it is unwinding it progressively decreases this effective diameter. Also in devices where fine wire is allowed to pile up on spools or drums it is difficult to maintain a constant tension on the wire and there is danger of the wire becoming tangled or being bent so sharply that it may be broken. When recording is done on wire which is wound onto, and piles up on, spools or drums it is usually necessary, after the recording is finished, to rewind the wire before reproduction of the recorded matter can be commenced.

My present invention overcomes the objections hereinbefore pointed out by providing a method of and means for handling the wire by winding it in a single layer on a drum of large diameter, and by passing said wire, or sections of said wire, through one or more recording or reproducing heads without transferring said wire from one drum to another. In this way I am able to keep the velocity of the wire constant, avoid tangling and breakage, reproduce without delay matter which has just been recorded, and attain other objects not attained by usual methods.

Other objects of this invention are to provide wire handling means for use with magnetic recording and reproducing devices of this nature which are simple in construction, reliable and efficient in operation, not expensive to manufacture, not liable to get out of order and which are especially well adapted for recording and reproducing audible sounds, as speech, music, and the like.

Other and more specific objects will be apparent from the following description taken in connection with the accompanying drawings.

In the drawings, Figure 1 is an elevation of a magnetic recording and reproducing device made in accordance with this invention.

Fig. 2 is a plan view of the same.

Fig. 3 is a front elevation of said magnetic recording and reproducing device.

Fig. 4 is a view in cross section substantially on broken line 4—4 of Fig. 2.

Figs. 5 and 6 are somewhat diagrammatic plan views of modified forms of this device, Fig. 6, being partly broken away.

Like reference numerals designate like parts throughout the several views.

Referring to the drawings, the numeral 10 designates a cylindrical drum having an axially disposed horizontal main shaft 11 which is supported for rotation in suitable bearings in end frames 12 and 13. The drum 10 is provided at 55

one end with a suitable groove 14 for the reception of a driving belt 15 which is connected with an electric motor 16. The motor 16 is reversible and may be capable of having its speed varied. 5 The end frames 12 and 13 are secured to a base 17 and preferably have their top portions connected by a transverse truss rod 18 which is positioned above the drum 10. Another truss rod 19, which also serves as a guide, connects the two 10 end frames 12 and 13 forwardly of the truss rod 18. A transverse lead screw 20 extends crosswise of the drum 10 just forwardly of the truss rod 19 and is journaled in the end frames 12 and 13. A combined truss and indicator bar 21 15 extends crosswise between the two end frames 12 and 13 at the front of the drum 10. An upright instrument board or panel 22 is secured to the forward portions of the side frames 12 and 13 adjacent the base 17. The base 17, panel 22, bar 21, and rods 19 and 18 cooperate with the end frames 12 and 13 to form a substantial and strong frame structure for the machine.

The lead screw 20 is driven by a link belt 23 which passes over two sprocket wheels 24 and 25 secured to the lead screw 20 and the main shaft 11 respectively. The sprocket wheel 24 is preferably of larger diameter than the sprocket wheel 25, providing for a reduction in speed between the shaft 11 and lead screw 20.

30 Two recording and reproducing heads, designated generally by numerals 26 and 27, are mounted on the lead screw 20 and guide rod 19. These heads are adapted to have recording wires 8 and 9 passed therethrough, as hereinafter described, for the purpose of subjecting said wires to electrical or electromagnetic forces to produce a record in said wires or to reproduce from said wires a record previously made, or to erase or eliminate and destroy a record previously made. 35 As this present invention is concerned only with the method of and means for handling the record wire, it is not deemed necessary to illustrate and describe the electrical and electromagnetic details of these recording and reproducing heads in this 40 application.

The recording and reproducing heads 26 and 27 are mounted on angle shaped bracket members 28 having notches 29 which fit over and are guided on the guide rod 19 and also having combined nut and hub portions 30 which are internally threaded and engage with the lead screw 20, which lead screw extends through said nut portions. The nut portions 30 also serve as bearing members for sheaves 31 and 32. Two of the 50 bracket members 28 are used in forming the mounting means for each head 26 and 27. These two bracket members are supported in spaced apart relation by the heads 26 and 27 and by the nuts 30 and by spacer members 33 which are 55 provided between the downwardly extending end portions of said bracket members 28. The lower end portions of the bracket members 28 are adapted to engage with electric switch means 34 and 35 as the heads approach the limit of their 60 travel in either direction to stop the motor before the heads reach the ends of the recording wires 8 and 9 which move through the heads. Preferably a switch arm 45 is connected with the lead screw 20 by friction means 46 for operating a 65 switch means 47. When lead screw 20 is rotating in one direction switch arm 45 will be yieldingly urged in a corresponding direction establishing a condition of switch means 47 which will render one head 26 or 27 operative and the other head 70 inoperative. When the direction of rotation of 75

the lead screw is reversed the condition of the heads as respects operativeness and inoperativeness will be reversed by reason of the switch arm 45 being yieldingly urged in the other direction. This reversal of the operating condition of the 5 two heads synchronously with reversal of the other parts occurs irrespective of whether the heads are conditioned for recording or reproducing.

I also preferably provide a reversing switch 10 means 48 supported on an adjusting screw 49 in a position where it will be engaged and operated by any suitable part which moves with the heads 26 and 27. This adjustable reversing switch means preferably has a pointer 50 movable over 15 indicator bar 21 to indicate the setting or adjustment of the same. For instance, if the pointer 50 is set at "3" on the indicator bar 21 it may mean that it will take three minutes of operation for the heads to move from a zero or starting position far enough to operate the reversing switch. The reversing switch 48 reverses the motor 16 and automatically starts the heads moving in a reverse direction when it is operated. As both heads move in synchronism only one reversing switch 20 25 is needed and this reversing switch may be manually adjusted to allow any period of operation within the limits of the machine. When the reversing switch 48 is in use the limit switch 35 at the right hand side of the machine will remain inoperative but in the event the reversing switch fails to operate properly this limit switch 35 will prevent damage to the machine.

In the device illustrated in Figs. 1 to 4, I have shown two pieces of recording wire 8 and 9 wound 35 on the drum 10. Each of these pieces of recording wire 8 and 9 has each end secured to the drum as indicated at 7 and each winding of wire has sufficient slack to permit one loop of the wire to extend outwardly through the adjacent head and 40 around the sheave connected with said head and back to the drum. The wire 8 extends through the head 26 and around the sheave 31 and the wire 9 extends through the head 27 and around the sheave 32. Obviously more heads and more 45 windings of wire may be provided, if desired.

Also it will be apparent that one continuous winding of wire of any desired length on a single drum may be provided with one or more loops feeding through one or more heads. In Fig. 5, 50 I have shown, somewhat diagrammatically a single piece of wire 36 wound on a drum 37 and having three loops 38, 39 and 40 passing through three recording and reproducing heads 41, 42 and 43. Obviously more than three heads may be 55 provided if desired and the wire may be passed through each head. The lead screw provides means for always moving the several heads in the same direction at the same rate of speed. In Fig. 6, I have shown two heads 51 and 52 positioned adjacent a drum in relatively angularly offset positions as respects each other and both having a recording wire 53 passed therethrough. Lead screws 54 and 55 are provided for the respective heads 51 and 52. By angularly offsetting the 60 heads 51 and 52 relative to each other it is possible to have a reproducing head following at any desired interval after the recording head and repeating the record at any interval after it is made. This makes it possible to provide delayed 65 speech or a delayed repetition of any series of electrical disturbances.

The pitch of the lead screw and the driving speed of the same are designed to impart the correct longitudinal movement to the heads when 75

the recording wire is wound in a single layer on the drum with the adjacent turns of wire lying side by side substantially in contact with each other. In practice, in a two head machine similar to the one shown in Figs. 1 to 4, I have successfully used five thousand feet of wire one one-hundredth (.01) of an inch in diameter on a drum fourteen inches in diameter and fifteen inches long, allowing substantially ninety-six wires to the inch when wound on the drum. This provides for making substantially a thirty minute record for loud speaker reproduction and substantially a one hour record for head phone reproduction, it being possible to record more matter on a given length of wire for head phone reproduction than for loud speaker reproduction.

When the wire is handled in the manner shown and herein before described I am able to move 20 the wire at a constant speed, to reduce wear and strain on the wire to a minimum, to avoid undue tensions on the wire, to eliminate the danger of snarling and tangling the wire and to reduce the danger of breaking the wire to a minimum. It 25 will be apparent that it is desirable to secure a constant even speed of the wire through the heads in order to obtain the best results.

In operation of the device shown in Figs. 1 to 4 the machine is set up, as shown, with the 30 two heads 26 and 27 positioned at corresponding locations in their respective sections of wire. To record on the wire said heads are set, by electrical control means not herein shown or described, so that they will record as distinguished from reproducing. When the machine is started the switch means 47 will energize one head and de-energize the other head. The machine is then permitted to run, with both heads moving in the same direction, for approximately half of the 40 period of time the particular piece of recording is to cover. The setting of the heads is then reversed preferably by the switches 48 and 47 so that the head which was previously recording will be de-energized and will not affect the wire 45 passing therethrough and the previously idle head will be caused to record. The heads are then moved in the opposite direction back substantially to the location or slightly past the location where they were at the commencement of the recording, the head which was de-energized and idle during the first half of the movement making the record during the last half of the movement and the head which made the record during the first half of the recording period being deenergized and idle during the last half of the recording period. The two heads, having been moved back to the starting position during the last half of the recording period will be properly positioned so that by again reversing the direction of 50 movement of these heads to move them in the original direction and by changing certain electrical controls, not herein specifically described, to cause the heads 26 and 27 to reproduce rather than record, the head which first recorded may be caused to immediately begin to reproduce what it recorded. After the first head has traversed all of the wire on which it recorded the direction of movement and condition of the heads 55 may again be reversed by switches 48 and 47 and the head which did the last half of the recording may be caused to reproduce what it recorded.

Each head is essentially provided with means, 60 not illustrated, to erase or eliminate from the

wire all previous records just prior to making a new record in said wire.

By handling the recording wire in the manner herein shown and described it is possible to record or reproduce with the wire moving in either direction through either head and to reproduce what has been recorded without any undesirable time delay between the time the recording is completed and the reproducing commenced. Also it is possible to transfer from one head to 10 another, at will, in recording and to easily follow these transfers in reproducing.

The foregoing description and accompanying drawings clearly disclose a preferred embodiment of my invention but it will be understood that 15 this disclosure is merely illustrative and that such changes in the invention may be made as are fairly within the scope and spirit of the following claims.

I claim:

1. In a magnetic recording and reproducing device, a rotatably mounted drum; reversible driving means connected with said drum; an electromagnetic head positioned adjacent said drum and clear of the drum; means providing 20 relative movement between the head and the drum in a direction longitudinally of the drum when the device is in operation; and a recording wire wound in a single layer on said drum, said recording wire having a loop portion passing off 25 of said drum and through said head and back onto said drum whereby said recording wire may be moved in either direction through said head by rotation of said drum.

2. In a magnetic recording and reproducing device, a rotatably mounted drum; reversible driving means connected with said drum; an electromagnetic head positioned near said drum; a recording wire wound in a single layer on 30 said drum and having both ends secured to said drum, said recording wire having a loop portion passing off of said drum and through said head and back onto said drum whereby without removing said wire from said drum, substantially the entire length of said recording wire may be 35 moved in either direction through said head by rotation of said drum, and means providing relative movement between said head and said drum in a direction longitudinally of the drum when the device is in operation maintaining said head 40 always in alignment with said loop portion of wire as said loop portion travels longitudinally of the drum.

3. In a magnetic recording and reproducing device, a rotatably mounted drum; reversible driving means connected with said drum; a plurality 55 of recording and reproducing heads positioned near said drum; a recording wire wound on said drum and having both ends secured to said drum, said wire having a plurality of loop portions each passing off of the drum and through one of the respective recording and reproducing heads and back onto the drum; and means providing relative movement between said heads and said drum in a direction longitudinally of the 60 drum when the device is in operation maintaining said heads always in substantial alignment with said loop portions as said loop portions travel longitudinally of the drum.

4. In a magnetic recording and reproducing 70 device, a rotatably mounted drum; a recording and reproducing head positioned near said drum; reversible driving means connected with said drum; a recording wire wound in a single layer on said drum and having both the ends thereof se- 75

cured to said drum said recording wire having sufficient slackness to provide a loop portion extending away from the drum and through the head; and means for moving said head lengthwise relative to said drum in directions parallel to the axis of the drum, said head moving means being synchronized with said drum driving means whereby said head and the loop portion of said wire are simultaneously moved in the same direction at substantially the same rate of speed.

5 10 15 20 25 30 35 40

5. In a magnetic recording and reproducing device, a rotatably mounted drum, two transversely spaced apart recording and reproducing heads positioned near said drum; reversible driving means connected with said drum; recording wire means wound in a single layer on said drum and having the ends thereof secured to said drum, said recording wire means having sufficient slackness to provide two loop portions extending away from the drum and through the respective heads; and means for simultaneously moving said two heads lengthwise relative to said drum.

6. In a magnetic recording and reproducing device, a rotatably mounted drum; a plurality of transversely spaced apart recording and reproducing heads positioned alongside of said drum; recording wire means wound in a single layer on said drum and having a plurality of loop portions extending away from the drum and through the respective heads and movable through said heads by rotation of said drum; reversible drum rotating means connected with said drum; and means for simultaneously moving all of said heads lengthwise relative to said drum in directions parallel to the axis of said drum, said head moving means being synchronized with said drum rotating means whereby said heads and the loop portions of said wire are simultaneously moved in the same directions at substantially the same rate of speed and a section of said wire is passed

in either direction through each of said heads without removing said wire from said drum.

7. In a magnetic recording and reproducing device, a rotatable mounted drum; a lead screw positioned alongside of said drum parallel to the axis thereof; a recording and reproducing head mounted on said lead screw; recording wire means wound in a single layer on said drum and having its respective ends secured to said drum, said recording wire means having a loop portion extending away from the drum and through the head and movable through said head by rotation of said drum; reversible drum rotating means connected with said drum; and lead screw driving means connected with said drum driving means for moving said head in directions parallel to the axis of said drum, said lead screw driving means being synchronized with said drum rotating means whereby said head and the loop portion of said wire are simultaneously moved in the same directions at substantially the same rate of speed.

8. In a magnetic recording and reproducing device, a rotatably mounted drum; a recording and reproducing head positioned near said drum; reversible driving means connected with said drum; a recording wire wound on said drum and having its end portions secured to said drum, said wire having a loop portion passing through said head; means synchronized with said drum rotating means for moving said recording head in directions parallel with the axis of said drum; control devices operated by said head moving means for simultaneously reversing the direction of rotation of said drum and the direction of movement of said head; and adjusting means connected with said control devices whereby said control devices may be selectively positioned for operation when said head has reached any predetermined location in its travel.

40 WILLIAM P. PATRICK.
